MILK BOTTLE TRAY

George Eugene Raymond, Lincoln, R.I., assignor, by mesne assignments, to Dari-Plastics, Inc., a corporation of Rhode Island

Filed June 7, 1961, Ser. No. 65,510

Term of patent 14 years

(Cl. D44—10)

FIG. 1 is a perspective view of the milk bottle tray, showing my new design; and

FIG. 2 is a section on substantially line 2—2 of FIG. 1.

I claim:

The ornamental design for a milk bottle tray, substantially as shown.
